US00D560209S

(12) **United States Design Patent** (10) **Patent No.:** **US D560,209 S**
(45) **Date of Patent:** **** Jan. 22, 2008**

(54) **SPEAKER**

(75) Inventors: **Yu-Guen Kim**, Gumi-si (KR);
Hyun-Seop Kim, Seoul (KR);
Chang-Hwan Hwang, Goyang-si (KR)

(73) Assignee: **Samsung Electronics Co., Ltd.**,
Suwon-Si (KR)

(**) Term: **14 Years**

(21) Appl. No.: **29/266,910**

(22) Filed: **Oct. 2, 2006**

(30) **Foreign Application Priority Data**

Aug. 23, 2006 (KR) 30-2006-0034707

(51) **LOC (8) Cl.** **14-01**

(52) **U.S. Cl.** **D14/215**

(58) **Field of Classification Search** D14/204,
D14/209-217, 168; 181/143-144, 147-148,
181/150, 157, 198-199, 151, 153; 381/300-302,
381/306, 333, 345, 361-364, 386-388, 332,
381/336; 348/14.01

See application file for complete search history.
